UNITED STATES PATENT OFFICE.

EDWARD W. BYRN, OF WASHINGTON, DISTRICT OF COLUMBIA.

FILE-BOX.

SPECIFICATION forming part of Letters Patent No. 291,574, dated January 8, 1884.

Application filed June 11, 1883. (No model.)

To all whom it may concern:

Be it known that I, EDWARD W. BYRN, a citizen of the United States, residing at Washington, in the District of Columbia, have invented a new and useful File-Box, of which the following is a specification.

The object of my invention is to provide a file box or receptacle for holding files of papers that are to be stored away, which box shall permit of ready inspection of its files and be easy of manipulation and simple and cheap of construction.

Figure 1 represents a perspective view of my invention from the rear end. Fig. 2 is a similar view, showing a modification; and Fig. 3 is a perspective view from the front of the box, showing a further modification.

A represents the front end piece. B is the bottom, and C C are the two sides, which parts are rigidly fastened together by brads or small nails.

D is the adjustable end piece, which corresponds to the front end piece, and is pivoted or hinged at its bottom, as shown at a, to swing upon either side of the vertical line.

E is the flexible cord, which may be either hard-twisted twine or woven curtain-cord. This textile cord may be supplanted by a chain, flexible wire, strap, or woven-wire cord; it being essential, however, that the cord or its equivalent shall be flexible, so as to be drawn in the direction of its length around angles. In Fig. 1 the two ends of the cord are fastened by screw-eyes b b to the two sides of the box, and the cord is laced through eyes or staples c c at the edges of the pivoted end piece, and passes behind the latter in the form of a bend or loop. The cord is made sufficiently long to permit the pivoted end piece to drop to the inclined position shown in dotted lines, and when the end piece is to be closed to its vertical position the bend of the cord is simply drawn down and looped over a nail, screw, or hook, d, on the back of the pivoted end piece.

In the modification shown in Fig 2, instead of a fastening device, d, on the back of the pivoted end piece, one end of the cord is provided with a ring, e, back of the screw-eye, which ring is hooked over a screw, hook, or nail, e', when the box is closed or allowed to slide down to the screw-eye and stop thereagainst, when the end piece is to be allowed to fall outwardly.

As a further modification, the cord, instead of being laced through screw-eyes or staples, may be laced through holes bored in the end pieces, 55 as in Fig. 3, and either looped over the fastening d on the pivoted end piece, as in Fig. 1, or over the front knob or pull, as in Fig. 3. In all these modifications it will be seen that there is a single cord extending from both sides of 60 the pivoted end piece, and the pivoted end piece is capable of being held in a vertical position, as shown, when the box is filled and closed, or in an outwardly-inclined position, as shown in dotted lines, when the box is opened 65 and the files loosened up for inspection, or in a position inclined inwardly from the vertical to hold the files tightly clamped when the box is not filled or several files are out for inspection. For the latter adjustment two or more 70 additional holding devices, d' d'', may be used, and the same duplication of holding devices e' of Fig. 2 can be resorted to.

In the construction of this box it will be seen that the amount of hardware is reduced to a 75 minimum, and the lumber is cut to the greatest advantage and with the least possible waste, as the two triangular side pieces may be cut from one rectangular section of board, and the two ends and bottom may be of equal width and 80 thickness and cut from the same board. Aside from its cheapness, the box is easily manipulated and the files quickly accessible. There are, moreover, no projections, either upon the outside of the box, to interfere with sliding 85 them in or out upon the shelves in close juxtaposition, or any projection on the inside, to interfere with the insertion of the files.

Instead of using triangular side pieces, C C, I may make them of a rectangular shape, if 90 desired.

I am aware that a file-box has been heretofore provided with an end piece pivoted or hinged at the bottom, and that wall-pockets and port-folios have had side pieces flexibly 95 connected to the body portion, and I do not claim any of these generic features.

I furthermore disclaim in this application the combination of a box and an end piece pivoted or hinged at the bottom with a rigid bail 100 whose ends connect with the side of the box and whose bend incloses the end piece. In this case the rigid bail merely acts passively as a stop to the outward movement and as a brace

to the inward movement of the end piece at certain definite points, while in the construction claimed by me in this application the cord roves through the eyes or staples, and is an active factor in adjusting the end piece, and is always at the same distance from the top of the end piece.

What I claim as new is—

1. The combination, with a file-box, of an end piece pivoted or hinged at its bottom, a cord-holding device fixed to one end of the box, and an adjusting-cord or its described equivalent passing through eyes in the side edges of the hinged end piece, and extending therefrom parallel with the sides of the box and connected with the box, as shown, the said cord being of such length as to adapt it to be deflected down to and around the holding device on the end of the box to close the latter, or be thrown up to allow the hinged end piece to fall back, as described.

2. The combination, with a file-box, of an end piece pivoted or hinged at the bottom to swing on either side of the vertical line, and a flexible adjusting-cord connecting the edges of the end piece to the box proper, the said end piece having a range of movement upon either side of the vertical, substantially as and for the purpose described.

3. The combination, with a file-box having a pivoted end piece, of a flexible cord or its equivalent, as described, connected at its ends to the sides of the box, and having its middle part looped around the end piece, and a fastening device for securing the cord when the end piece is drawn to a closed position, as set forth.

EDWD. W. BYRN.
